UNITED STATES PATENT OFFICE.

JAMES S. DOYLE, OF NEW YORK, N. Y.

METALLIC WINDOW-FRAME FOR STEEL CARS.

No. 873,218.

Specification of Letters Patent.

Patented Dec. 10, 1907.

Application filed January 24, 1907. Serial No. 358,840.

To all whom it may concern:

Be it known that I, JAMES S. DOYLE, a citizen of the United States, residing at New York, county of New York, State of New York, have made a certain new and useful Invention in Metallic Window-Frames for Steel Cars, of which the following is a specification.

This invention relates to metallic window frames for steel cars.

The object of the invention is to provide a construction of metallic window frames for steel cars, which is simple in construction and efficient in operation.

15 A further object is to provide a metallic box girder of suitable configuration to efficiently receive and guide the window sash.

20 A further object is to provide an efficient and simple construction of metallic window framing for steel cars, in which the sash are self adjusting, operate without undue rattle, and are held and guided in their raising and lowering movements.

25 Other objects of the invention will appear more fully hereinafter.

The invention consists substantially in the construction, combination, location, and relative arrangement of parts, all as will be more fully hereinafter set forth, as shown in the 30 accompanying drawing, and finally pointed out in the appended claims.

35 Referring to the accompanying drawing, and to the various views and reference signs appearing thereon,—Figure 1 is a broken view, in horizontal section, of a metallic window frame for steel cars, embodying the principle of my invention. Fig. 2 is a front elevation of the same, the window curtain being removed. Fig. 3 is a detail edge view 40 of the spring employed to take up wear and to enable the sash to adjust itself and to be held without noise or rattle in its frame.

45 The advent of the modern steel car, for street and other railway use, has given rise to the necessity for new construction for various parts of the equipment of the car, in order to meet the requirements of the changed conditions of the car structure. In 50 the case of the car windows it is found that the wooden frames are objectionable for the reason that they not only unnecessarily increase the size and weight of the car but they are also not adapted for use in connec-

tion with the adjacent metal parts, and, moreover, by reason of the contraction and 55 expansion of the metal parts of the car framing, the wooden windows become warped causing the sash to bind therein, or else they become loose, causing an annoying and an objectionable noise and rattle and inducing 60 rapid wear and destruction of the frame as well as the sash.

It is among the special purposes of my present invention to avoid the objections noted, and to provide a metallic window 65 frame for use in steel or similar cars which is light, strong, durable, and well adapted for use in combination and association with the adjacent metal parts of the car framing, and whereby warping or looseness through ex- 70 pansion and contraction is avoided, and wherein the sash are efficiently held and guided, and adjust themselves to their frame, and are held against undue noise and rattle and with the least possible wear in the rough 75 usage to which the operation of street or other cars are subjected.

In carrying out my invention I provide a window frame in the form of a sheet metal plate, preferably shaped into the form of an 80 open sided box girder, and which, if desired, may form a portion of the framing of the steel or other car body. The side surfaces of this box girder, one or both, depending upon its position, are suitably shaped to 85 form channels to receive metallic channel castings or blocks in which the metallic side bars of the sash are received, held and guided, a leaf spring or bow shaped spring strip being interposed between the edge of the sash 90 bar and its receiving channel casting in order to enable the sash to be self adjusting and held and guided without noise, rattle or undue wear.

Referring to the accompanying drawing 95 A, designates the metallic sheet or plate shaped into the form of a box girder, the sides of which may be shaped into suitable channels and guide beads to accommodate the window frame castings and sash and the 100 window curtains. In the drawing I have shown a box girder A, shaped on each of its sides to receive two window frame channel castings B, C, and the end of the curtain fixture D. In this respect, however, I do not 105 desire to be limited or restricted as the con-

figuration of the sides of the box girder may be made to conform with any desired number of window frame castings or curtains. In the particular form shown the sides of the 5 box girder are shaped to form the channels E, and F, the former adapted to receive and form a seat for the channel castings B, and the latter adapted to receive and form a guide for the shade or curtain fixtures D. 10 Intermediate the channels E, and F, the sides of the box girder are formed into a bead or ridge G, against which are received and bear the channel castings C, which are co-operatingly shaped. The edges of the box girder 15 are formed into flanges H, to which is bolted, riveted or otherwise secured the plate or panel K. The part L, of the box girder between adjacent windows may be flush with the inner wall of the car and be finished off 20 in any suitable or desired style of ornamentation. The castings B, are in the form of boxes having an outwardly presented open side. These castings are preferably of some light strong metal. I have found that 25 aluminium castings are admirably adapted for my purposes. These castings conform in contour to the shape of the seats or channels E, and are snugly received therein, the outer side surfaces of said castings lying against 30 the inner surfaces of the edge flanges H, of the box girder, said flanges serving to form one side of the seats E. The inner corners of the castings are inclined to conform to the inclined portion of the surface of the seats E, 35 produced in the formation of the adjacent beads G. The castings C, on the inner edges thereof, are shaped to form a seat for, and to snugly receive, the beads G, of the box girder sides, as clearly shown, the inner side surface 40 of the outer casting B lying and bearing against the outer side surface of the adjacent inner casting C. The side bar M, of the outer sash is preferably of metal and is received through the open side of the casting B, 45 which it snugly fits, and in which it is guided in its movements when such sash is raised or lowered.

In practice, I prefer to form the side bar M, of strong light metal, such, for instance as 50 aluminium. This side bar, as shown, is hollow and is provided on its outer edge with a seat in which is received the edge of the window pane N, a gasket or strip of rubber, felt, or other suitable material, indicated at O, 55 serving as a lining for the pane seat in the sash side bar M. Similarly, the sash side bar P, of the inner sash is received and guided within the channel formed in the casting C, and the pane R, of the inner sash is received 60 in a seat formed in the outer edge of such bar P, and lined with rubber, felt or other suitable material, as shown.

In order to enable the sash to adjust themselves within the channel castings and to 65 prevent any looseness and the consequent

noise and rattle, I place a bow shaped or curved spring strip S, within the castings B, and C, and between the outer edges of the side bars M, and P, and the bottoms of the channel castings, as clearly shown.

The interior of the hollow box girder forms a chamber in which, if desired, may be received a sash counterweight, indicated at W, and suitably connected to the sash. I do not claim this feature herein, however, as 75 the same forms the subject matter of a separate application filed Jan. 29, 1907, Serial No. 354,624.

From the foregoing description it will be seen that I provide an exceedingly simple 80 construction and arrangement of metal window frames for steel cars, wherein the sash are efficiently held and guided in their channel castings, and are self adjusting therein, wherein the noise and rattle incident to the 85 rough usage of cars in service and the wear of such use, are avoided, wherein looseness or binding due to expansion or contraction is avoided and wherein strength, durability and lightness are most admirably combined. 90 It will also be seen that the box girder being a metal plate rolled or bent into the desired shape, may be produced at very little cost thereby materially reducing the cost of construction of a car. It will also be seen that 95 since the window sash operate in metallic guidings or channels which are not subject to the warping effect due to variations in temperature the sash may be readily and easily moved in their guideways or channels 100 at all times and may be accurately and neatly fitted thereto without danger of the closeness of the fit being interfered with or being destroyed. It will also be seen that a window embodying the principles of my invention affords efficient protection against 105 the penetration around the sash of the weather, rain snow or wind, and even under the heavy pressure of a high wind the sash may still be readily and easily operated.

While I have shown and described my invention as applied to steel street or railway cars, it is obvious that the same is equally well adapted to other structures, as houses, 115 automobiles, ship, boats and the like. I do not desire, therefore, to be limited or restricted in respect to the situation in which my invention is to be used.

It is obvious that many variations and changes in the details of construction and 120 arrangement would readily suggest themselves to persons skilled in the art and still fall within the spirit and scope of my invention. I do not desire, therefore, to be limited or restricted to the exact and specific details of construction and arrangement shown and described. But

Having now set forth the object and nature of my invention, and a construction embodying the principles thereof, what I claim 130

as new and useful, and of my own invention, and desire to secure by Letters Patent is:

1. The combination with a window sash, of a metallic box girder having a channel formed in the side thereof a box casting fitted to said channel and adapted to receive and guide the side bar of the sash.
2. The combination with the window sash, of a metallic sheet or plate, shaped to form a hollow box girder, and having channels and beads in the sides thereof box castings fitted to said channels and beads and adapted to receive and guide the sash.
3. In a metallic window frame for steel cars, a metal plate bent to form a box girder, and having the sides thereof shaped to form channels and beads, metal sash bars, and means fitting said channels and beads for receiving and guiding said sash bars in the sliding movement of the latter.
4. In a metallic window frame for steel cars, a box girder having the sides thereof shaped to form channels, box castings fitting in said channels and metal sash bars received and sliding in said castings.
5. The combination with a box girder having channel seats formed in the sides thereof, open sided channel castings received in and fitting said channel seats, sash bars received and sliding in said channel castings and bow springs interposed between said channel casting and said sash bars.
6. The combination with a box girder having channel seats and beads formed in the sides thereof, open sided metallic box castings fitting said channels, similar box castings fitted to said beads and sash bars received in and guided by said box castings.
7. The combination with a box girder having the sides thereof shaped to form channels and beads, opensided metallic box castings respectively fitting in and fitted to said channels and beads, sash bars received in and guided by said box castings, and bow springs fitted between the edges of said sash bars and the bottoms of said box castings.
8. In a metallic window frame for steel cars, a metal plate bent to form a box girder, and having the sides thereof shaped to form channel seats and beads, and terminating in lateral flanges, metal box castings seated in said channels and bearing against said flanges, other metal box castings having their inner edges shaped to conform to and fitting said beads, and arranged adjacent to the first mentioned box castings, all of said box castings presenting outwardly an open side, hollow metal sash bars received in and guided by said box castings, and each having a seat to receive a window pane, and a bow spring interposed between the edge of each sash bar and the bottom of its associated box casting.

In testimony whereof I have signed my name to this specification, in the presence of two subscribing witnesses, on this 17th day of January A. D. 1907.

JAMES S. DOYLE.
